UNITED STATES PATENT OFFICE.

ELIZABETH MARABLE BRENNAN, OF BROOKLYN, NEW YORK.

DRESS-SHIELD.

1,108,427.

Specification of Letters Patent. Patented Aug. 25, 1914.

Application filed January 31, 1914. Serial No. 815,843.

To all whom it may concern:

Be it known that I, ELIZABETH MARABLE BRENNAN, a citizen of the United States of America, residing at Brooklyn, in the county of Kings and State of New York, have invented certain new and useful Improvements in Dress-Shields, of which the following is a specification.

My invention relates to improvements in dress shields, an article worn at the arm holes in women's garments to prevent perspiration from penetrating the material of the garment.

One of the principal objects of my invention is to provide an improved form of dress shield which, owing to the construction and correlated arrangement of its constituent parts, may be easily kept in a thoroughly sanitary condition.

A further object is to so construct the shield that the rubber pad or layer used in such shields, may be readily removed and washed; and as the rubber is generally the most expensive portion of the shield, as well as that which most readily retains the odor of perspiration, the facility with which the rubber pad of my improved shield may be removed and inserted, effects both a saving in cost of material and a decided increase in cleanliness.

A still further object, is to provide a part of the shield with a pocket or receptacle to receive an antiseptic or fragrant substance, which is rendered active by the heat of the body of the wearer.

The invention comprises the features hereinafter claimed, and fully described in the following specification, reference being had to the accompanying drawing, 40 wherein—

Figure 1 is a side elevational view, parts being broken away, of my improved shield; and Fig. 2 is a vertical sectional view, on the line 2—2 of Fig. 1, looking in the direction of the arrows.

Dress shields are generally substantially crescent shaped, to fit the arm hole of a dress, and my improved shield is illustrated as having this form, although it will be understood that variations in shape may be readily made.

In the dress shield illustrated, 10 and 11 denote the outer walls, which are made of any suitable fabric. The walls are each substantially crescent shaped, normally lie parallel to each other, and are connected at

their upper edges by stitching 12. The inner walls of the shield, 13 and 14, are also made of suitable fabric, and substantially correspond in shape with the walls 60 10 and 11. The inner walls lie at opposite sides of the arm hole of the dress, while the outer walls are nearest the body of the wearer. I prefer to provide one of the inner walls with a pocket or receptacle 15, designed to receive an antiseptic or fragrant substance 16.

Adapted to be interposed between the inner and outer fabric walls of the dress shield, is a pad or sheet of rubber consisting of the preferably integral layers 17 and 18, both of which are substantially crescent shaped, in order to correspond with the shape of the fabric walls. It is my purpose to removably secure the inner and outer 75 fabric members together, and also to removably attach the rubber insert pad between the inner and outer walls, as more particularly shown in Fig. 2. With these ends in view, I provide about the inner peripheries 70 of the outer walls 10 and 11, and about the outer peripheries of the inner walls 13 and 14, suitable fastening members, which are also designed to pass through the insert pad at its periphery. The fastening means 80 preferably consist of snap fasteners, each comprising a male member 19 which may be secured to the inner wall 13 or 14, and a female member 20, which may be secured to the outer wall 10 or 11. The male members 19 pass through orifices at the periphery of the rubber pad, and into the female members of the fasteners, thus securing the fabric members together and retaining the rubber between the fabric. 95

To obviate the necessity of stitching the dress shield to the dress, I may provide near each of the upper side edges of the shield, a hook 21 which may be engaged by an eye 22 carried at the end of a band or cord 23, 100 adjustable in length and designed to encircle the arm, which band acts to support the shield in position.

In assembling a shield embodying my invention, the rubber insert pad is first laid 105 over the inner member 13—14, then the outer member 10—11 is placed over the rubber layer, and the snap fasteners are closed. To disassemble the device, the hooks are simply opened, whereby the rubber pad may 110 be removed for cleaning, and the fabric members may be washed. The snap fas-

teners are spaced some distance from each other, so as to form ventilating spaces there-between.

Having thus described my invention,
5 what I claim is:

A dress shield, comprising a pair of crescent shaped outer walls of a single thickness of fabric, connected at their upper edges, a flexible insert member comprising
10 a pair of integral crescent shaped walls, the upper edge of said member resting under the upper connected edges of the outer fabric walls, a pair of crescent shaped inner walls of a single thickness of fabric and hav-
15 ing their upper edges connected and lying

immediately under the upper edge of said flexible member said inner and outer walls being separate from each other, and means arranged about the inner peripheries of the outer and inner fabric walls and passing 20 through the periphery of said flexible insert member for releasably connecting the latter and said inner and outer fabric walls together.

In testimony whereof I have affixed my 25
signature in presence of two witnesses.

ELIZABETH MARABLE BEENNAN.
